2 SHEETS—SHEET 2.

UNITED STATES PATENT OFFICE.

RUDOLF KLICKA, OF PITTSBURGH, PENNSYLVANIA.

DENTIST'S CABINET.

1,388,347.

Specification of Letters Patent. Patented Aug. 23, 1921.

Application filed November 16, 1920. Serial No. 424,358.

To all whom it may concern:

Be it known that I, RUDOLF KLICKA, citizen of the United States, and residing in the city of Pittsburgh, in the county of Allegheny and State of Pennsylvania, have invented or discovered the new, useful, and Improved Dentists' Cabinets, of which the following is a specification.

My invention consists in certain new and useful improvements in dental cabinets.

The object which I have in view is the provision of a combination cabinet which combines the function of a cabinet for conveniently containing the necessary tools and other requisites for oral work, with the function of a dental laboratory and work bench.

With this object in view, I have invented a new and improved combination cabinet provided with suitable compartments or drawers for tools and other requisites for oral work within easy reach and access of the dentist while working on a patient's teeth, and which is in addition provided with the power tools, such as drills, grinding wheels, buffers and rotary brushes, required for dental laboratory work.

The cabinet is provided with means for collecting and carrying away the dust and refuse resulting from laboratory work, and filtering the same from the air, so that the same do not float in the atmosphere of the room nor settle on the furniture. Means are also provided for the thorough separation from such dust of the valuable gold and other metal particles without loss.

Other novel features of construction and arrangement of parts will appear from the following description.

In the accompanying drawings, which are, however, merely intended to illustrate a practical embodiment of the principles of my invention without limiting the scope of the latter to the construction shown, Figure 1 is a front elevation of a combination cabinet embodying the principles of my invention; Fig. 2 is a vertical section taken along the irregular line II—II in Fig. 1; Fig. 3 is a vertical section taken along the line III—III in Fig. 2; Fig. 4 is a horizontal section taken along the line IV—IV in Fig. 2; Fig. 5 is a broken perspective taken in section along the line V—V in Fig. 3, and on a slightly enlarged scale; and Fig. 6 is a detail section along line VI—VI in Fig.

1 the drawer being shown pulled out to expose the section port. Fig. 7 is a perspective of the air filter.

The following is a detailed description of the drawings:

The cabinet, which, is preferably of wood but which of course may be made of metal, is shown as of the following construction.

1 represents the vertical side walls, 2 the back and 3 the top.

4 is the working shelf horizontally supported by the side and back walls at a convenient height. Above the shelf 4 are the two spaced apart shelves 5 and 6. 7 represents vertical partitions spaced inwardly from the sides 1, thus forming with the sides 70 and back and with the shelves 5 and 6, compartments which are divided by the short horizontal shelves 8 to receive the small drawers 9 for storing tools and other supplies.

10 is a vertically disposed box or duct whose rear wall is formed by the back 2 and which extends from an opening or port 11 in the rear center of the shelf 4, through the rear center of the shelf 5, to a port 12 in 80 the rear center of the shelf 6.

The rear or inner portion of the space between shelf 6 and the top 3 is inclosed by the removable door or closure 13 which is disposed in the upwardly and outwardly inclined position shown in Fig. 2 bearing against top and bottom horizontal cleats 14, and held in position by pivoted buttons 15 which engage slots in the inner surfaces of the sides 1.

Thus an upwardly expanding filter chamber 16, extending the full width of the cabinet is formed. To one side of its transverse axis, the top 3 is provided with a port 17 which is connected by the conduit 18 with 95 the intake of an electrically driven fan A whose discharge 19 may be open to atmosphere.

Within the chamber 16 is removably mounted an air-filter which is preferably of the following construction.

20 represents wooden or other solid ends which are connected together and suitably spaced apart by the longitudinal top and bottom braces 21, 22 represents a covering of cheese cloth or other textile material which is stretched on said frame, inclosing the same except the top which is open. The end

pieces 20 are provided at their tops with horizontally disposed flanges 23, whose under surfaces are slightly inclined downwardly toward the front. The sides 1 of the cabinet within the compartment 16 are provided with horizontally disposed cleats 24 upon which the flanges 23 ride when the filter is introduced into the compartment 16. The inclination of the flanges 23, having a wedging engagement with the cleats 24, causes the top edge of the filter to be forced up into snug engagement with the under side of the top 3 of the cabinet. The port 17 is positioned to open into the interior of the filter. The textile filter walls are spaced away from the front and rear walls of the compartment 16, as shown in Fig. 2, and the bottom of the filter is somewhat above the shelf 6. Thus air sucked by the fan A through said compartment from the port 12 to the port 17 must pass through the filter, depositing on the walls all dust and other foreign matter, so that the fan may discharge its air into the room without contaminating the atmosphere.

The filter may be removed at suitable intervals for cleaning off the materials deposited from the air on its walls, the valuable elements, such as small particles of gold being recovered, and dust deposited on the floor and walls of the compartment 16 may be swept out and its valuable elements separated.

25, 25^a, 25^b, 25^c, 25^d and 25^e are partitions extending from the shelves 4 and 5, and forwardly from the back wall 2 but stopping short of the front edge of the shelf 4. Thus a central compartment 26 is formed to accommodate an electric motor B. Also four working compartments 27, 28, 29 and 30 are formed, and two relatively narrow end compartments 31 and 32, which may be used for storage or display.

In front of each compartment 31 and 32 I depend a lamp support 33 from the shelf 5 carrying an incandescent lamp 34 to illuminate the working shelf 4.

35 represents the motor shafts extending from either end of the motor B across the fronts of the working compartments, the partitions being notched, as at 36 in Fig. 5, to provide clearance for the shafts, so that the rotary tools 37 mounted on the shafts, such as grinding wheels, buffers, brushes, &c. 55 are substantially half within the working compartments.

38 represents a dust receiver or hopper mounted under the shelf 4 against the back wall 2. The lower end of the duct 10 connects with the top center of the hopper by means of the port 11 through the shelf 4.

In the rear of each working compartment the shelf 4 is ported, as at 39 in Fig. 4, for the full width of the compartment, thus 65 forming openings through said shelf con-

necting the working compartments with the interior of the hopper.

40 represents sliding valve members, preferably in the form of drawers, one of which is provided for each working compartment. 70 When said drawers are shoved back into the compartments, said ports are closed. By drawing out a drawer, as shown in Fig. 4, the corresponding port 39 will be opened.

The rear portions of said drawers 40 are 75 provided with double deflecting shields or lids 41, facing front and rear, so that when a drawer is pulled out, exposing the corresponding port 39, the dust and dry particles from the tools will be deflected down into the 80 port 39 while the pumice paste or other liquid will be deposited in the front of the drawer.

The bottom or throat of the hopper 38 is provided with a removable box 42 into 85 which the gold or other heavy metallic particles drop to be recovered.

43 represents a box with inclosed and opaque sides and front and whose back is formed by the front wall of the duct 10; said box depending from the shelf 6. 44 represents posts extending from the shelf 5 to the lower front corners of said box. The bottom, 45, of said box is a glass plate, and 46 is a glass plate filling in the space between 95 the posts 44, the shelf 5 and the box 43. Thus the space between the bottom of the box 43 and the shelf 5 is therefore provided with a transparent glass wall or shield in front but is open at the sides. 47 is a lamp 100 support depending in the box 43 and provided with a lamp 48 which illuminates from above the space in shelf 5 below the box 43.

C is a dental engine mounted on the top 3 105 so that its flexible driving shaft 49 may be either turned up out of the way, or turned down as shown in Fig. 1, so that its drill chuck may be inserted, from the side, under the box 43, as shown.

50 is a door or closure in the front wall of the duct 10 below the box 43. When said door is opened, the dust from the working operation carried on back of the glass shield 46 will be sucked into the duct 10.

D represents an apron or closure, preferably made of metal and hinged along the front of the shelf 4. Said apron is provided at its ends with a pair of pivotally attached braces 51 whose slotted ends are engaged by 120 the headed pins 52 on the sides 1 which limit the opening movement of the apron and support it in its open, horizontal position. The apron is preferably provided near its inner edges with a trough 53 which serves to catch 125 materials or substances rolling or moving off the shelf 4. When turned up and secured, the apron acts as a closure for the shelf 4 and the compartments floored thereby, thus concealing and protecting their contents. 130

54 represents storage drawers for tools, supplies, &c., fitted between the sides 1 below the shelf 4 and in front of the hopper 38.

When work is to be done on this shelf 4, 5 the door 50 is closed and all of the drawers 40 are pushed in to cover the ports 39, except in the case of the working compartment in front of which the work is to be done. In the case of said compartment, the drawer is 10 drawn forward until the apex of its shield is under the motor shaft, and thus exposing the corresponding port 39. Thus, while the pumice paste discharged from the rotary tool, and similar liquids are thrown down 15 into the front incline of the shield and thus caused to run down into the interior of the drawer, the remaining refuse and dust is directed toward and sucked down the port 39 into the hopper 38, the heavier elements, 20 such as particles of gold falling down into the removable recovery box 42, while the lighter material is sucked up the duct 10 into the chamber 16 wherein the air is sucked through the filter walls 22, depositing the 25 dust and other suspended materials on said walls, while the filtered air is discharged by the fan to atmosphere. The filter may be removed at proper intervals for cleaning its walls and the recovery of valuable material 30 therefrom.

Also the chamber 16 may be swept of precipitated dust.

When work is to be done on the shelf 5 under the box 43, all of the ports 39 are 35 closed and the door 50 opened. The work is held under the glass bottom 45 and in the rear of the glass shield 46 and the drill or other tool on the end of the flexible engine shaft is applied thereto, the hands of the 40 operator being inserted from the sides.

The work is illuminated by the lamp in box 43, but the opaque walls of the box prevent the light shining into the operator's eyes.

45 The door 50 is opened, thus causing all dust and refuse to be sucked back into the duct 10, as heretofore indicated.

From the foregoing is apparent that my combination cabinet is a very advantageous 50 and convenient piece of furniture inasmuch as it fulfills all the purposes and requirements of both operative or oral and laboratory work.

Although, for the sake of clearness, I have 55 minutely described the embodiment of the principles of my invention illustrated in the drawings, I do not wish to limit myself thereby, but claim broadly;

1. In a cabinet of the character described, 60 the combination of a working compartment inclosed at the bottom, top, sides and rear and adapted to contain a power tool, a port in the floor of said compartment, a drawer 65 slidably mounted on the floor of said compartment and adapted when pushed in to

close said port, means for applying suction to said port for the withdrawal of the dust and refuse caused by the operation of said tool, and a rearwardly inclined deflector carried by said drawer and adapted when 70 said port is open to direct said dust and refuse into said port.

2. In a cabinet of the character described, the combination of a working compartment inclosed at the bottom, top, sides and rear 75 and adapted to contain a power tool, a port in the floor of said compartment, a drawer slidably mounted on the floor of said compartment and adapted when pushed in to close said port, means for applying suction 80 to said port for the withdrawal of the dust and refuse caused by the operation of said tool, and a double pitched reflector on the rear portion of said drawer adapted when said port is open to direct the dry dust and 85 refuse toward said port and the liquid refuse forwardly into said drawer.

3. In a cabinet of the character described, the combination of a plurality of horizontally aligned working compartments, a container 90 for dust and refuse beneath said compartments, a port connecting each of said compartments with said container, sliding drawers in said compartments adapted to open and close said ports, and means for 95 applying suction to said container.

4. In a cabinet of the character described, the combination of a plurality of horizontally aligned working compartments, a receiving 100 container beneath said compartments, said compartments being individually connected with said container by means of valved ports, vacuum producing means in the upper part of said cabinet, and a duct leading from said container to said 105 means.

5. In a cabinet of the character described, the combination of a plurality of horizontally aligned working compartments, a receiving 110 container beneath said compartments, said compartments being individually connected with said container by means of valved ports, an air-filter in the upper part of said cabinet, a duct connecting said container with one side of said filter, and vacuum producing means connected to the other side of said air-filter.

6. In a cabinet of the character described, the combination of a plurality of horizontally aligned working compartments, a receiving 120 container beneath said compartments, said compartments being individually connected with said container by means of valved ports, a chamber in the upper part of said cabinet, a duct connecting the lower 125 portion of said chamber with said container, a textile air-filter in said chamber, and vacuum producing means connected to the upper part of said chamber.

7. In a cabinet of the character described, 130

the combination of a plurality of horizontally aligned working compartments, a receiving hopper beneath said compartments and connected to each of the latter by means of 5 valved ports, a chamber in the upper part of said cabinet, a duct connecting the lower portion of said chamber with said hopper, vacuum producing means connected to the upper portion of said chamber, and a 10 textile air-filter mounted in said chamber to intercept the current of air sucked through the same.

8. In a cabinet of the character described, 15 the combination of a plurality of horizontally aligned working compartments, a receiving hopper beneath said compartments and connected to each of the latter by means of valved ports, a removable closure for the throat of said hopper for the removal of 20 heavy particles of refuse, a chamber in the upper portion of said cabinet, a duct connecting said hopper with said chamber, a vacuum producing means connected to the upper portion of said chamber, an air-filtering 25 means mounted in said chamber and intercepting the traveling air.

9. In a cabinet of the character described, 30 the combination of a plurality of horizontally aligned working compartments, a receiving hopper beneath said compartments and connected to each of the latter by means of 35 a valved port, a vertical duct having its lower end connected to said hopper, and means for applying suction to the upper end of said duct.

10. In a cabinet of the character described, 40 the combination of a plurality of horizontally aligned working compartments, a receiving hopper beneath said compartments and 45 connected to each of the latter by means of a valved port, a vertical duct having its lower end connected to said hopper, means for applying suction to the upper end of the duct, and a removable box forming the closure for the throat of said hopper.

11. In a cabinet of the character described, 50 the combination of a compartmented working shelf, a container beneath said shelf, a port connecting each of said compartments with said container, valves for said ports,

an air filter, communicating with said container, and means for applying suction to said filter.

12. In a cabinet of the character described, 55 the combination of a working shelf, a container beneath said shelf, a port connecting said shelf with said container, an air filter above said container, an air duct connecting said container with one side of said filter, and means for applying suction to the other 60 side of said filter.

13. In a cabinet of the character described, 65 the combination of a working compartment having a transparent top and provided with suction means for the removal of the refuse of working, and a lamp compartment above 70 said working compartment and whose floor is formed by the transparent top of said working compartment, and said lamp compartment being provided with an opaque front wall to prevent the light shining into the eyes of the operator.

14. In a cabinet of the character described, 75 the combination of a working compartment having a transparent top and provided with valved suction means for the removal of the refuse of working, and a lamp compartment above 80 said working compartment and whose floor is formed by the transparent top of said working compartment, and said lamp compartment being provided with an opaque front wall to prevent the light shining into the eyes of the operator.

15. In a cabinet of the character described, 85 the combination of a working compartment having a transparent top and front wall, the sides of said working compartment being open, and said working compartment being provided with suction means for the removal of the refuse of working, and a 90 lamp compartment above said working compartment, the floor of said lamp compartment being formed by the transparent top of said working compartment and the front wall of said lamp compartment being opaque 95 to prevent the light shining into the eyes of the operator.

Signed at Pittsburgh, Pa., this 13th day of November, 1920.

RUDOLF KLICKA.
